H. W. JACKSON,
SUPPORT FOR INCANDESCENT LAMP FILAMENTS,
APPLICATION FILED JAN. 9, 1908.

UNITED STATES PATENT OFFICE.

HENRY W. JACKSON, OF EAST ORANGE, NEW JERSEY, ASSIGNOR TO WESTINGHOUSE LAMP COMPANY, A CORPORATION OF NEW YORK.

REPORT FOR INCANDESCENT-LAMP FILAMENTS.

1,150,270.

Specification of Letters Patent. Patented Aug. 17, 1915.

Application filed January 9, 1903. Serial No. 410,042.

To all whom it may concern:

Be it known that I, HENRY W. JACKSON, a citizen of the United States, and resident of East Orange, county of Essex, State of New Jersey, have invented certain new and useful Improvements in Supports for Incandescent-Lamp Filaments, of which the following is a specification.

The present invention relates more particularly to incandescent lamps having filaments of tungsten, tantalum or other metals, which when formed into threads of such thinness as to serve as the incandescence bodies in such lamps are found to be fragile or liable to become bent or distorted so as to come into contact from opposite sides and thus produce undesirable or disastrous short circuits.

It is well known, that, in the tungsten incandescent lamp, for example, the filament is an extremely fine thread of tungsten and that generally speaking, if it is desired to form this thread into loops, as is requisite for use in lamps at the usual commercial voltages, this looping must be done during the original forming process and not after the metallization has been completed. To provide the necessary lengths, a number of looped filaments are connected in series with 30 in the same lamp bulb and such filaments are supported at their ends and at their loops by rigid hooks, or the like. In order to provide the necessary supporting medium, a rod of glass is usually extended through the middle of the lamp bulb to a point not far from the outer end thereof, and the hooks or other supports are secured in this rod or extension at or near its ends. One terminal of the first filament and one terminal of the last filament are attached to hooks or supports secured in the interior stem of the lamp and joined to wires leading, respectively, to the lamp terminals on the base.

When a tungsten filament, or a series of such filaments constituting in effect one filament, is supported in the manner described, it sometimes happens that a filament becomes broken through a jarring of the lamp, such rupture being partly due to the rigidity of the filament supports. Sometimes, also, even if the filament is not broken it sags under the influence of gravity or is thrown out of alinement by some other cause, in

which case different parts of the filament 55 may come together and form a short circuit.

The object of the present invention is to string the thread or threads, of tungsten or other material substantially as heretofore, except that at one end of the bends, turns or 60 loops of the filament are elastically supported upon bodies having considerable mass, or a high melting point, whereby the filament is kept taut by the resiliency of the springs, the sagging of the filament is prevented by 65 the same action and whereby the loops are prevented from fusing to their supports by reason of the considerable surface of contact and the mass of such supports, or the character or material of the supports. 70

I am aware that it has been proposed to provide springs made of twisted wire for supporting the loops at various points, but the wire used for this purpose presents so little mass and surface of contact and has 75 so low a melting point that it is liable to become excessively heated and the filament may readily become fused thereto.

In my improvement, I make use of flat springs formed into or having attached to 80 them rings or other supporting shapes. The rings, if attached, may be of nickel or some other suitable metal, or preferably of thorium, and in any case they may have considerable mass and surface of contact, so that the 85 rings are not exposed to the danger of becoming excessively heated, that is to say, are kept cool enough to prevent the occurrence of fusion between them and the supported loops of the filament. 90

The drawing hereto annexed is an elevation of a lamp base and lamp, the lamp itself being shown mainly in section for the sake of clearness.

In the drawing, 1 is a lamp bulb, and 2, 95 22 and 222 are filaments of tungsten or other fragile material. To the stem, 3, of the lamps are secured hooks or supports, 4 and 5, to one of which one terminal of the filament, 2, is suitably joined.

Through the middle of the lamp bulb runs a glass rod, 6, forming an extension of the stem, 3, and provided with an enlargement, 7, near its inner end and an enlargement, 8, near its outer end. To the enlargement, 7, 100 are secured, in the present instance, two V-shaped supports, 9 and 10, of metal, the butt of the V being the part which in each in-

stance is embedded in the enlargement, 7, while the ends of the V extend outward as shown to form the needed support.

To the enlargement, 8, are secured three flat springs, 11, 12 and 13, each being bent over near its outer end and attached to one or the other of three rings, 14, 15 and 16, as shown. The rings, 14, 15 and 16, may be replaced by other shapes, but in any case the 10 mass of the support and its surface of contact are made such that the filament will not fuse to the support. With thoria as the supporting substance, the danger of such fusion is still further lessened, inasmuch as 15 this substance is a good electrical insulator and has a high-melting point. The same would be true of other so-called rare earth oxids, most of which might be substituted for thoria without departing from the spirit 20 of the present invention.

Tracing the incandescence element from the end connected with the support, 4, it will be seen that the filament, 2, passes first to and through the ring, 14, back to one end, 25 of the support, 9. The filament, 22, joined to the other end of the said support, passes to and through the ring, 15, back to one end of the support, 10. Finally, the filament 222, joined to the opposite end of the support, 10, passes to and through the ring, 16, and back to the other terminal support, 5.

The springs, 11, 12 and 13, are preferably of comparatively slight resiliency and are put under moderate tension when the filament is originally strung through the rings attached thereto. Thus there will never be any extreme force exerted upon the filament such as would rupture it or endanger it in 35 any way.

40 It is found that lamps constructed in this way may be transported with less danger of breakage than when the filaments are rigidly supported as is now the custom. Moreover, with spring supports such as I 45 have described, allowance is made for the expansion of the filament under the influence of heat and its contraction after the interruption of the current as well as the normal contraction, observed in the length

of the filament as a whole during extended 50 use.

It will be understood that the invention may be applied to filaments of other material besides tungsten, tantalum, or molybdenum, and in some instances may be found 55 useful in connection with ordinary carbon filaments commonly used in incandescent lamps.

It will be further understood that the springs themselves may be widened and 60 increased in mass at their outer ends so as to require no intermediate rings or other shapes, although in practice I usually prefer that the springs and the rings should be made of different materials, or at least from 65 different pieces of materials and attached together by suitable means.

I claim as my invention:

1. An incandescent lamp comprising a main support, a reversely bent filament, and a resilient device secured at one end to the support and supporting the bight of the filament at its other end, thereby maintaining the legs of the filament under tension, the ends of the resilient device that are attached to the filament being of greater mass than the remainder thereof. 70

2. An incandescent lamp comprising a filament, and a resilient filament support maintaining the filament under tension and 80 bent to present a plurality of portions thereof of adjacent each other for engagement with the filament.

3. An incandescent lamp comprising a filament and a resilient filament support maintaining the filament under tension and bent 85 to present a plurality of portions thereof adjacent each other for engagement with the filament, the said portions being composed of a material having a high melting point. 90

Signed at New York, in the county of New York, and State of New York, this 4th day of January, A. D. 1908.

HENRY W. JACKSON.
